UNITED STATES PATENT OFFICE.

LOUIS SCHNEIDER, OF CLINTON, MISSOURI.

TYPEWRITER-CARRIAGE RETURN.

1,363,619.

Specification of Letters Patent. Patented Dec. 28, 1920.

Application filed November 19, 1919. Serial No. 339,020.

To all whom it may concern:

Be it known that I, LOUIS SCHNEIDER, a citizen of the United States, residing at Clinton, in the county of Henry, State of Missouri, have invented a new and useful Typewriter-Carriage Return; and I do hereby declare the following to be a full, clear, and exact description of the invention, such as will enable others skilled in the art to 10 which it appertains to make and use the same.

The invention relates to typewriter carriage returns and has for its object to provide means adjacent the typewriter keys and 15 keyboard and mounted in the front edge of the frame whereby the carriage may be returned to its initial position by simply sliding a slidable member transversely, thereby obviating the necessity of the operator raising 20 the hand from the keyboard for spacing and shifting the carriage. This is a distinct advantage where the operator uses the touch system as it keeps the hands practically in position over the keys of the keyboard at 25 all times.

A further object is to provide a carriage return and spacing means comprising a slidable member slidably mounted in the slot in the front of a typewriter frame, said slidable member being spring tensioned and provided with a pulley over which a cord passes. One end of said cord is permanently fixed and the other end leads to and attached to the carriage and its spacing means 35 so that when the slidable member is moved longitudinally the initial pull on the cord will cause a roller spacing operation and a further pull will cause the carriage to be returned to its initial position.

With the above and other objects in view the invention resides in the combination and arrangement of parts as hereinafter set forth, shown in the drawings, described and claimed, it being understood that changes 45 in the precise embodiment of the invention may be made within the scope of what is claimed without departing from the spirit of the invention.

In the drawings:—

Figure 1 is a sectional view through a portion of the front frame of a conventional form of typewriter.

Fig. 2 is a sectional view taken on line 2-2 of Fig. 1.

Fig. 3 is a perspective view of the slidable member.

Referring to the drawings, the numeral 1 designates the front extension of a typewriter frame which extension extends around the key board of the machine. The 60 front rail 2 is provided with a longitudinally disposed elongated slot 3, in which slot a slidable member 4 is slidably mounted. Member 4 on its upper and lower edges is provided with longitudinal grooves 5 which 65 engage the inner and outer walls of the front bar 2 and form means, whereby the member 4 will be prevented from becoming displaced. Slidable member 4 is provided with inwardly extending horizontally disposed 70 spaced ears 6 between which ears a pulley 7 is rotatably mounted on a pin 8. Extending around the pulley 7 is a carriage operating cord 9, the end 10 of said cord extending through a longitudinally disposed aperture 75 11 in the slidable carriage shifting member 4 and having its end secured as at 12 in the left hand side of the elongated slot 3, thereby forming a stationary securing point for the ends 10 of the cord 9. The 80 portion 13 of the cord 9 passes over a pulley 14, thence over pulleys located in any suitable manner on the machine and has its end secured to the line space lever of the machine.

It is obvious that this securing means will have to be varied considerably according to the type of carriage and its shifting means. However, it is understood that the portion 13 of the cord 9 may be led to the spacing 90 and shifting mechanism of the carriage according to the type of carriage and that any amount of leads may be used in reaching said spacing and shifting mechanism of the carriage. Secured to the slidable member 4 95 as at 15 is a coil spring 16, the other end of said spring being secured as at 17 to the frame 1. It will be seen that as the carriage during a writing operation feeds toward the left that a pull will be imparted 100 to the portion 13 of the cord 9 in the direction of the arrow *a* which will stretch the coiled spring 16, the function of said coiled spring being to maintain the cord taut during a shifting operation or during a writing 105 operation. During the writing operation when it is desired to space the roller and shift the carriage back to its initial position to the right, the finger of the operator is placed in engagement with the finger engaging member 18 of the slide 4. Then the slide 4 is moved in the direction of the arrow 110

5 which will cause a pull to be imparted on the portion 13 of the cord 9 which cord passes over the pulley 7 and has its end anchored as at 12. Thus it will be seen that 10 as the slidable member 4 is moved in the direction of the arrow *a* with the end of the portion 13 connected to a conventional form of spacing and shifting mechanism carried by the carriage said mechanism will space 15 the roller on the initial sliding movement of the slide 4 and further movement of the slide will cause the return of the carriage to its initial position to the right.

From the above it will be seen that a carriage shifting device is provided which will be positive in its operation and one wherein it will not be necessary for the operator to move the hands from the key board to space the roller and return the carriage to 20 the initial position. It will also be seen that a carriage shift is provided which is simple in construction and one which may be easily and cheaply constructed.

The invention having been set forth what 25 is claimed as new and useful is:—

1. A carriage return for typewriters comprising a member slidably mounted in a guide slot of the typewriter frame adjacent the key board, a pulley carried by said slid- 30 able member, a cord having one of its ends anchored to one end of the guide slot, said cord passing over the pulley carried by the slide member and having its free end connected to the line space lever, and spring 35 means whereby as the carriage moves in one direction or the other said cord will be maintained taut.

2. A carriage return for typewriters comprising a slidable member, said slidable member being mounted in a horizontally disposed guide slot in the frame of the machine adjacent the key board, said slide being provided with longitudinal grooves on

its upper and lower edges for engaging the frame adjacent the slot, a pulley carried by 45 the slide, a cord having one of its ends anchored in the end of the guide slot, said cord passing over the pulley and thence to the line space lever, and a coil spring having one of its ends connected to the slide 50 and its other end anchored to the typewriter frame and forming means for maintaining the cord taut during the shifting of the carriage from one side to the other.

3. A carriage return for typewriters comprising a slidable member, said slidable member being mounted in a horizontally disposed guide slot in the frame of the machine adjacent the key board, said slide being provided with longitudinal grooves on 60 its upper and lower edges for engaging the frame adjacent the slot, a pulley carried by the slide and disposed in a pocket thereof, a longitudinally disposed aperture in the slide and substantially tangent to the outer 65 edge of the pulley, a carriage controlled cord having one of its ends anchored in the end of the guide slot, said cord extending through the longitudinal aperture over the pulley and having its free end secured to 70 the carriage spacing and returning lever, a coiled spring connected to the slide and also to the frame of the typewriter for maintaining the cord taut during a writing operation, and a finger engaging member 75 carried by said slide whereby the slide may be moved longitudinally to return the carriage to its initial position.

In testimony whereof I have signed my name to this specification in the presence of 80 two subscribing witnesses.

LOUIS SCHNEIDER.
